UNITED STATES PATENT OFFICE.

HENRY J. STUART, OF DERBY, CONNECTICUT, ASSIGNOR TO ROBERT N. BASSETT COMPANY, INCORPORATED, OF SHELTON, CONNECTICUT, A CORPORATION OF CONNECTICUT.

BUTTON-CLASP.

1,283,954.

Specification of Letters Patent.

Patented Nov. 5, 1918.

Application filed August 15, 1916. Serial No. 114,963.

To all whom it may concern:

Be it known that I, HENRY J. STUART, a citizen of the United States, residing in Derby, in the county of New Haven and 5 State of Connecticut, have invented a certain new and useful Improvement in Button-Clasps, of which the following is a specification.

My invention relates to button clasps for 10 garment supporters and like articles, but more particularly to that class of the same in which the button is provided with an elastic collet, and its fundamental features are illustrated and described in my co-pending 15 application Serial No. 849471, filed July 7, 1914. The object of my invention is to construct a button of this character in which the collet will co-act with a slotted base plate to fasten the button tape to the button. A 20 further object is to construct a button in which the collet is so shaped that it will present oppositely disposed faces which will co-act with the button loop to fasten the garment.

25 I attain these and other objects of my invention in the device set forth in the following description and accompanying drawings in which like reference characters refer to corresponding parts.

30 In the drawings:

Figure 1 is a front view of one form of button clasp to which my invention is applied;

Fig. 2, a central longitudinal section taken 35 on line $x-x$ in Fig. 1 but showing the button loop swung forwardly out of engagement with the button;

Fig. 3, a detail view showing the manner in which the button is threaded before it is 40 attached to the clasp;

Figs. 4 and 5, detail views of a modification; and

Fig. 6, a detail view of a further modification.

45 The button clasp generally consists of an attaching link A, a button loop B and a button tape C which carries a button D at its lower extremity. The button loop B, which is connected to the lower side of the attaching link A by a strap E projecting from the upper side thereof, is provided with a bridge F and has the sides of its lower extremity contracted to engage the shank of the button D. With the exception of the button D and 50 the manner of attaching the same to the

tape C, the device thus far described is one of the common forms of button clasps well known in the art and is merely disclosed herein for the purpose of showing how my invention is applied. Referring to Figs. 1, 2 and 3, the button D consists of a base plate 2 to which is riveted an outwardly projecting stud 3 provided with a head 4. Slipped over the stud 3 and held against the base by the under side of the head 4 is an apertured 60 spring rubber collet 5 which is shaped to form a head 6, a neck or shank 7 and a flange 8. The under side of the head 6 and the upper side of the flange 8 are spaced a predetermined distance apart to present oppositely disposed faces 9 and 10 respectively. The under side of the flange 8 overlaps the slots 11 and 12 in the base plate 2 so that the periphery or edge of the flange will nearly close the middle portion of the slots leaving 70 the ends of the slots open. The base plate 2 is threaded with tape by inserting one corner of the end 13 of the tape rearwardly through one of the open ends of the lower slot 11. The tape is then pulled through the slot 75 from its rear side and passed forwardly through the upper slot 12 in a like manner. During the threading of the base plate the overlapping edge of the flange 8 will yield sufficiently to permit the passage of the tape. 80 The flange 8, however, is sufficiently resilient to co-act with the outer edges of the slots to grip the tape and fasten it to the button. The tape is secured to the clasp by passing 85 its end 14 forwardly through the link A, then rearwardly through the loop B over the top of the bridge E. Both ends 13 and 14 are then fastened together by stitches 15, 15, the end 13 being folded in to prevent fraying. The neck 7 and the oppositely disposed faces 9 and 10 of the collet co-act with the upper and lower faces and the inner edge 90 of the loop B, which is shown made of sheet metal, to grip the stocking or other garment.

Referring to Figs. 4 and 5, wherein the collet is shown made in two pieces, the flange 16 projects beyond the slots thereby presenting a greater gripping surface 17 on its under side. Its top side is provided with a seat 18 for the reception of the lower end of 100 the neck 19 depending from the head 20. In this modification the parts may be assembled by first threading the base 21 with the tape and then pressing successively the two parts of the collet over the head 22 of the stud. 105 110

It should be observed that the utilization of the elastic collet of the character above described enables me to secure the tape to the button without stitching the same at its button end unless desired, and further when the parts are assembled by slipping the collet over the head of the stud, which is the preferred way of assembling, the operation can be performed by hand. It should be noticed also that the flange of the collet substantially conceals the metal between the slots in the base thereby enhancing the appearance of the button.

Referring to Fig. 6, the collet 23 has the periphery of its flange 24 undercut or rounding off on its under side so that the overlapping edges of the flange do not obstruct the free passage of the folds in the tape when it is desired to fasten the latter by sewing.

I have herein referred to the collet as being made of spring or elastic rubber but my invention is intended to include all like collets made of other elastic or springy material.

While the preferred forms of my invention are embodied in the devices above described, yet the same are susceptible to such further modifications as may fairly come within the scope of the appended claims.

Having now described my invention what I claim and desire to protect by Letters Patent is:

1. A button clasp comprising a loop and button, the said button being provided with a stud and an elastic collet mounted on said stud, the said collet having oppositely dis-

posed faces spaced apart by an elastic neck and the said faces being arranged to co-act with the upper and lower sides of the loop.

2. A button for button clasps comprising a slotted base plate provided with a projecting stud, fabric material threaded through said base plate and an elastic collet having a neck surrounding said stud, the said collet being provided with an outwardly projecting flange at its lower extremity which overlaps the slots and co-acts with said base plate to grip the fabric material.

3. In a button clasp a button comprising a slotted base plate on which is mounted a headed stud, the said base plate being threaded with tape, and an elastic collet surrounding said stud and held against the tape by the under side of the head of the stud, the said collet being provided with oppositely disposed co-acting faces spaced apart by a neck.

4. A button for button clasps comprising a slotted base plate, a tape passed through said slots, a stud projecting from the face of said base plate between the slots, an annular elastic disk slipped over said stud, the diameter of said disk being greater than the distance between the slots, and an elastic collet having a shank and head surrounding said stud in front of said disk, the said elastic members filling the space between the base and the head of the stud.

In testimony whereof I have hereunto set my hand this 27th day of July 1916.

HENRY J. STUART.
